DRYING MACHINE.

1,414,973.

Specification of Letters Patent.

Patented May 2, 1922.

Application filed August 14, 1920. Serial No. 403,479.

To all whom it may concern:

Be it known that we, THOMAS ALLSOP and WALTER W. SIBSON, citizens of the United States, residing in Philadelphia, in the county of Philadelphia and State of Pennsylvania, have invented certain new and useful Improvements in Drying Machines, whereof the following is a specification, reference being had to the accompanying drawings.

Our invention relates to drying machines, our principal object being to provide for easy and flexible control of the flow of air by which drying is effected. By means of apparatus embodying our invention in its more complete form, we are able to vary the direction of flow or circulation of the air through the drying space of the machine; its angle or direction of impingement on the material or articles to be dried; and the quantity of air coming in contact with the material,—all, if desired, more or less independently of one another. How these and other advantages can be obtained in connection with our invention will be made apparent by the description hereinafter of the best embodiment at present known to us, while its scope and essentials in its various phases and aspects will be indicated in our claims.

In the drawings, Fig. I is a side view of a drying machine embodying our invention, in mid-section.

Fig. II is a sectional elevation at right angles to Fig. I, taken at a plane corresponding to the line II—II in Fig. I, the uppermost tray shown being also in section.

Referring to the drawings, it will be seen that the drying machine here shown comprises an enclosure 1 with suitable top and side walls, the bottom being formed by the floor on which the machine rests. In this enclosure 1 is a chamber or space for the material to be dried, here shown in the form of a compartment 2 in the lower portion of the enclosure toward the front thereof: i. e., in its lower front corner. Convenient access to the interior of the drying compartment 2 may be had through a door 3 at the front of the enclosure. In the enclosure is also an auxiliary compartment or passage 4 which extends part way around the drying compartment 2 and serves, in the operation of the machine, as a means of connection

and communication between adjacent sides of the drying compartment 2,—the sides thus connected in the present instance being the top and the rear. A flow of air as drying medium through the compartment 2 in contact with the material to be dried may be produced by a fan 5 mounted in said passage 4 adjacent the angle between the aforesaid sides of the compartment which are connected through said passage. As shown, this fan 5 is located in a circular opening in an upright partition or diaphragm 6 extending from the top of the drying compartment 2 to the roof of the enclosure 1, so as to form, in effect, an extension upward of the rear wall of said drying compartment. This fan 5 is mounted on a horizontal shaft 7 which extends lengthwise of the enclosure 1, and may be driven in either direction by means of a pulley 8 mounted on its left-hand end outside the rear enclosure wall. It will be seen that the roof of the enclosure 1 over the drying compartment 2 has a considerable slope, so as to aid in the direction of the air and reduce eddies. By rotation of the fan 5 in either direction, a circulation of air may be produced in the enclosure 1, with flow one way through the drying compartment 2 and return through the auxiliary compartment or passage 4. In its flow either way through the passage 4, the air may be heated by means of a bank of steam pipes or coils 9 mounted at the rear of the drying compartment 2. Openings 10 controlled by slides 11 may be provided for admitting fresh air and discharging moisture-laden or contaminated air.

As shown, provision is made for supporting the articles or material to be dried in the compartment 2 in a plurality of substantially horizontal tiers, by means of shelving or trays 12 that rest and slide on angle-iron guides 13 at the sides of the enclosure and at the rear of the compartment 2. These trays 12 need not extend the full width of the compartment 2 from front to rear, but may be somewhat shorter, as shown, so as to afford an air circulation space at their front ends, adjacent the door 3 through which they are inserted and removed. The trays 12 may also have permeable bottoms (see Fig. II) in the nature of grids or

wire netting, to permit passage of air directly through them as well as horizontally amongst them.

The direction of flow of the air through 5 the drying compartment 2,—whether downward into the same at its upper side and out at its left hand side, or vice versa,—may be controlled, as before indicated, by the direction of rotation of the fan 5. Provision is 10 made for controlling and varying the direction or angle of entry of the air into the compartment 2 and its direction or angle of impingement on the articles or material to be dried by means of deflector shutters or 15 slats 15 pivoted at opposite ends in bars 16 which are secured to the frame-work 17 of the drying compartment structure; these shutters can also be used as dampers or valves for controlling and varying the available 20 passage for the air and the flow thereof. As shown, there is one series 20 of such deflectors 15 at the top of the compartment 2 and another series 21, in which the slats are somewhat wider, at the rear of said compartment. The deflectors of the series 20 25 can be moved and adjusted in unison by means of a horizontal slide bar 22 to which they are connected by links 23. This bar extends out through the wall of the enclosure 30 1 above the door 3 and has a series of notches 24 for engagement with said wall as a means of securing it and the deflectors controlled thereby in adjusted position. The deflectors of the series 21 may be operated in unison 35 by means of an elongated double crank 25 to which they are all connected by short links 26. The ends 27 of this crank 25 are pivotally mounted in lugs 28 secured to the framing 17. This crank 25 may be actuated 40 by means of a horizontal slide rod 30 pivoted thereto and extending out through the wall of the enclosure 1 at 31.

It will readily be seen that with the apparatus described, articles or material in the 45 drying compartment 2 may be acted on by air passing therethrough and coming in contact therewith from either direction, according to the direction of rotation of the fan 5. The direction of impingement of the air on the articles,—whether from above 50 through the series of deflectors 20, or from the rear through the series 21,—may be further adjusted and varied by adjustment of said series of deflectors 20 and 21. These 55 adjustments can be made independently, and when one of said series of deflectors is in use to control the direction of the impingement of air, the other can be used valve-wise to vary and control the available 60 passage for the air and the flow thereof.

Having thus described our invention, we claim:

1. A drying machine comprising an enclosure with a compartment therein for the 65 materials to be dried and a passage directly

connecting adjacent sides of said compartment; means for circulating air in said enclosure, with flow one way through said drying compartment and return through said passage; and means in the aforesaid 70 adjacent sides of said drying compartment for varying and controlling the flow of air therethrough and its direction of impingement on the material therein.

2. A drying machine comprising an enclosure 75 with a compartment therein for the material to be dried, and a passage directly connecting the top of said compartment with a side thereof; means in said compartment for supporting material to be dried in horizontal tiers; means for circulating air in said enclosure, with flow either way through said compartment and return through said passage; and means in the top and the side of said compartment connected therewith by 80 the aforesaid passage for controlling and varying the direction of the entering air.

3. A drying machine comprising an enclosure 85 with a compartment therein for the material to be dried, and a passage directly connecting the top of said compartment with a side thereof; horizontal shelving in said compartment for supporting material to be dried; means for circulating air in said enclosure, with flow either way through said 90 compartment and return through said passage; and means in the top and the side of said compartment connected therewith by the aforesaid passage for controlling and varying the direction of the entering air; and a series of adjustable horizontal air-directing 95 and controlling shutters across the top of said compartment and at the side connected therewith by the aforesaid passage. 100

4. A drying machine comprising an enclosure 105 with a compartment therein for the material to be dried, and a passage directly connecting the top of said compartment with a side thereof; means in said compartment for supporting material to be dried in horizontal tiers; means in the top and the side of said compartment connected therewith by the aforesaid passage for controlling and varying the direction of the entering air; a series of adjustable horizontal air-directing 110 and controlling shutters across the top of said compartment and at the side connected therewith by the aforesaid passage; and a fan in the aforesaid passage adjacent the angle between the top and side of said compartment connected thereby for circulating the air through the compartment with return through the passage. 115

5. A drying machine comprising an enclosure 120 with a compartment in its lower front portion for the materials to be dried and a passage connecting the top and rear sides of said compartment; means for circulating air in said enclosure, with flow one way through said drying compartment and 125 return through the passage. 130

return through said passage; and means in the aforesaid adjacent sides of said drying compartment for varying and controlling the flow of air therethrough, and its direction of impingement on the material therein.

6. A drying machine comprising an enclosure with a compartment in its lower front portion for the materials to be dried and a passage connecting the top and rear 10 sides of said compartment; fan means in said passage above the top of said compartment for circulating the air therein, with flow one way through said compartment, and

return flow through said passage; and means for varying and controlling the flow of air and its direction of impingement on the material in said drying compartment.

In testimony whereof, we have hereunto signed our names at Philadelphia, Pennsylvania, this 12th of August, 1920.
